UNITED STATES PATENT OFFICE.

JAMES S. SNODGRASS AND JAMES B. CARTER, OF EMINENCE, KENTUCKY.

FASTENER FOR COVERS OF CRATES.

1,151,057.

Specification of Letters Patent. Patented Aug. 24, 1915.

Application filed November 30, 1914. Serial No. 874,777.

To all whom it may concern:

Be it known that we, JAMES S. SNODGRASS and JAMES B. CARTER, citizens of the United States, residing at Eminence, in the county 5 of Henry and State of Kentucky, have invented certain new and useful Improvements in Fasteners for Covers of Crates; and we do hereby declare the following to be a full, clear, and exact description of the invention, such as will enable others skilled in 10 the art to which it appertains to make and use the same.

This invention relates to fasteners for covers of crates such as are adapted to contain 15 eggs and the like for shipment.

The object of the invention is to provide simple, durable and convenient locking means for such crates, which locking means may not be released without detection.

20 With this object in view the invention consists in the improved construction, arrangement and combination of parts hereinafter fully described and afterward specifically claimed.

25 An approved embodiment of the invention is illustrated in the accompanying drawings in which like reference characters mark the same parts in all of the figures, and in which—

30 Figure 1 represents in elevation, the front of the crate, closed, locked and sealed; Fig. 2, a section on the plane indicated by the broken line 2—2 of Fig. 1; and Fig. 3, the rear of the crate in elevation, showing the 35 hinges.

In the drawings, 1 indicates the crate having a lid 2, provided at its front and rear with strips 3 depending over the top edges of the sides 4 of the crate. The crate has 40 strips 5 across the front and back faces of the same thickness as the strips 3 of the lid, but spaced below said strips 3 to allow of the space 6 therebetween. The usual partitions 7 are formed in the crate, assisting 45 in transversely supporting the lid 2. In the rear space 6, suitable eye screws 8 are positioned in strip 5, while suitable screw hooks 9 are mounted in the strip 3 adapted to register with the eye screws 8 so that their 50 hooks may be engaged in the eye portions of the screws 8 to form detachable hinges, whereby the lid 2 may first be opened and then removed. The front strip 3 has suitably positioned therein, eye screws 10 and

55 closely adjacent thereto are the eye screws 11 which are mounted in the front strips 5 so that the eye portions will register when the lid is closed. A locking rod 12 is then passed through the eye screws 10 and 11 to lock said cover closed. One end of the 60 locking rod 12 is bent at a right angle as at 13 which is turned downward into a groove 14 so that said locking rod will be retained against longitudinal displacement. To insure the retention of the angular portion 13 65 in the groove 14, a seal 15 is pasted or otherwise suitably fastened upon the face of the front strip 5 and across the groove 14. This seal likewise serves to show the address or destination of the crate when in shipment 70 and also acts as an indicator to show whether the crate has been forcibly opened as it would be impossible to raise the angular portion 13 without breaking the seal.

The form herein shown and described is a 75 preferred embodiment of the invention, but such alterations and variations may be made therein as will not depart from the spirit of the invention nor the scope of the claim.

Having thus fully described our invention 80 what we claim as new and desire to secure by Letters Patent of the United States is:—

A crate provided with a horizontal strip 85 secured upon the front thereof below the upper edge, and provided with a vertical groove in the face thereof, a lid provided with a strip upon its front edge depending over the front of the crate when the lid is closed, leaving a space between the two strips, eye screws depending from the cover 90 into said space, eye screws set in the upper edge of the body strip projecting also into said space with the eyes of all of the screws registering, a locking rod adapted to pass through the eyes of the screws and provided 95 with an end bent at an angle to cause it to seat in the groove of the body strip when turned down, and a seal pasted over the groove to secure the angular end of the locking rod therein.

In testimony whereof we have signed our names to this specification in the presence of two subscribing witnesses.

JAMES S. SNODGRASS.
JAMES B. CARTER.
